UNITED STATES PATENT OFFICE

WILLIAM A. BARNES, OF TOLEDO, OHIO, ASSIGNOR TO THE SWARTZBAUGH MANUFACTURING COMPANY, OF TOLEDO, OHIO, A CORPORATION

DESIGN FOR AN ELECTRIC ROOM HEATER

Application filed October 7, 1931. Serial No. 41,330. Term of patent 14 years.

To all whom it may concern:

Be it known that I, WILLIAM A. BARNES, a citizen of the United States, residing at Toledo, in the county of Lucas and State of Ohio, have invented a new, original, and ornamental design for Electric Room Heater, of which the following is a specification, reference being had to the accompanying drawing, forming a part thereof, in which:

The figure is a perspective view of the article showing my new design.

I claim:

The ornamental design for an electric room heater, substantially as shown.

WILLIAM A. BARNES.
